MECHANISM FOR HOLDING UMBRELLA COVER TIPS IN STITCHING POSITION

Martin M. Cohn, Brooklyn, N. Y., assignor to
Michael M. Scharf, Long Beach, N. Y.

Application July 13, 1940, Serial No. 345,319

5 Claims. (Cl. 112—114)

The present invention relates to apparatus for sewing attachments to umbrella covers, and the like, and more particularly to attachments having a single eye or opening, such as umbrella tips, and the like.

As it is well known, at the present time, the edges of umbrella covers, particularly that of ladies' umbrellas, are frequently not directly secured to the ribs of the umbrella, but are provided with tips which are secured at the corners of the umbrella cover segments and are fitted over the ends of the umbrella ribs, to retain the cover on the ribs.

It is the object of the present invention to provide apparatus of the character described which will enable one to secure the attachment named above to the umbrella cover on the same sewing machine which was heretofore used for sewing buttons thereon, thereby making possible great economy in plant equipment.

It is a further object of the present invention to devise apparatus of the character described which are particularly adaptable to be conveniently and easily used for attaching the tips to an umbrella cover.

It is a further object of the present invention to provide apparatus of the character described which will attach tips to umbrella covers in a manner that will leave the edge of the cover smooth and continuous, and will eliminate the necessity for allowing an excess of material, as required with apparatus at present in use, thereby resulting in the double advantage of economy in the use of material and a minimum of strain along the edge of the umbrella cover, at the point where the strain is greatest.

It is the object, generally, of the present invention to provide apparatus of the character described, which is of highly simplified construction, easy and convenient to use, which is durable and economical, and which is highly efficient for its purposes.

Heretofore tips were attached to the cover either by hand or by relatively complicated mechanism especially constructed for that purpose.

It is the general object of the present invention to provide apparatus wherewith the operations described may be performed on one and the same machine on which the buttons are sewn. This object is, broadly speaking, attained by the provision of novel attachments for button sewing machines by means of which umbrella cover tips may be accurately and conveniently held in position to be stitched to the associated fabric by the vibrating needle of the machine.

In the accompanying drawing there is shown one embodiment of the sewing machine and attachments of the present invention. It is to be understood, however, that such embodiment is shown by way of illustration only, to make the principles and practice of the invention more readily comprehensible, and is not intended, in any way, to limit the scope of the invention to the details therein shown.

10 In the drawing:

Fig. 1 is a view in perspective of one embodiment of the apparatus of the present invention showing a tip sewing attachment in position with a tip arranged therein;

15 Fig. 2 is a fragmentary top plan view of the apparatus of Fig. 1;

Fig. 3 is a side elevational view of the tip retaining arm shown in Figs. 1 and 2;

20 Fig. 4 is an enlarged cross-sectional view, taken through the eye of an attached umbrella tip;

Fig. 5 is a plan view of an arm retaining a button ring in operative position; and

25 Fig. 6 is a side elevational view of the arm shown in Fig. 5.

25 Referring more specifically to the accompanying drawing, the sewing machine, which is generally designated as 10, is of the general type having a vibrating needle bar 11, in which is arranged the needle 12, and which moves the needle laterally and transversely of the machine, as well as reciprocating it perpendicularly to the work plate of the machine. One sewing machine found suitable for the purpose is that made by the Singer Manufacturing Co., under its catalog Number 175-60. It is to be understood, however, that any other machine having similar characteristics may be conveniently used.

The machine 10 has a work plate 13 in which there is arranged the needle plate 13', having the 30 needle slot 14 through which the vibrating needle 12 is reciprocated. The machine is also provided with a pivoted bar, or lever 16, which extends along the work plate 13 and is raised thereabove, to the free end of which button guides are normally attached.

40 In order to convert such machine 10, for the purposes of this invention, there is secured near the free end of the lever 16, an L-shaped bracket 17, one arm 18 of which is supported from the lever 16 and the other arm 18' at 45 right angle to the arm 18 and substantially parallel to the lever 16, provides a space around the needle bar for the manipulation of materials by the operator.

50 On the bracket arm 18' there are provided two channelled portions or grooves. One channel 19

is located, preferably, at a point intermediate the end of the lever 16 and a point opposite the needle bar 11 and is provided with shoulders 20 and a threaded opening 21. An arm 22 is arranged within the channel 19 and is rigidly held therein by the shoulders 20 and by the set screw 23 passing through a slot 24 in the arm and engaging in the threaded opening 21. The arm 22 is arranged to extend forwardly, in direction of the needle and to one side thereof, and is provided with a downwardly offset end, at the extremity of which is carried an enlarged portion or head 25, which normally rests on the work plate 13. The head 25 is provided with an aperture 26, within which there may be adjustably arranged and secured by set screw 27, any suitable means for retaining an umbrella tip 29. To facilitate adjustment, the screw 27 may be set into a diagonally disposed face 28 on the head 25.

The tip retaining means may be of any suitable type, such as the tubular member 30, which receives the tip 29, internally, and which may be provided with the wing portions 31 to support the tip 29 in place. The member 30 is so arranged that it will support the tip 29 in position to have its eye 32 lie directly above the needle slot 14 at a point approximating the position of the needle at one extreme of its vibrating movement.

It will be readily seen that when the tip 29 is arranged within the retaining means 30 the edge of an umbrella cover may be placed around the rounded end of the tip, which projects from the member 30, with the inner face of the cover 33 facing the tip, as is normally required to be done when sewing one object or fabric to another on a sewing machine. The machine is then set into operation and, as it will be obvious, the needle 12, as it reciprocates and vibrates, will pass, alternately, once through the eye 32 of the tip 29 and the fabric surrounding it, and once to the side of the tip, either through the fabric or alongside of it, in a chain stitch formation. The cover will thus be secured to the tip by stitches extending only from the center of the tip to one side thereof, to provide a smooth and continuous surface to the edge of the umbrella cover, without any tucks or folds as heretofore produced in machine attachment of the tips.

When the stitching is completed, the tip 29 may be easily removed from its retaining means 30 and turned to face the inside of the cover 33, and when in that position may be seated over the end of an umbrella rib, in a manner well known to those skilled in the art.

The arm 18' may be provided with a groove 35 defining shoulders 36 and with a threaded opening 37 and adapted to receive a second arm 38 in substitution for the arm 22 when the latter is removed from its place. The arm 38 extends directly toward the needle 12 and is provided with a downwardly offset end, which normally rests on the needle plate 13' of the machine; the said end being provided, preferably, with a forked extremity 39, passing about the needle slot 14. Also provided on the end of the arm 38, directly to the rear of the needle slot 14, is an upright pin or post 40, which is arranged in such position relative the needle 12 that when a button ring 41 is arranged about the post 40 and held thereagainst, a portion of such ring 41 may be arranged over the needle slot 14 in position to permit the vibrating needle to pass to either side of the portion of the ring lying over the needle slot, so as to stitch a fabric about the ring, in a manner which will be readily understood.

When the ring 41 is to be secured between two folds of material, instead of to a band, as is the case when such ring is attached to a folding umbrella case, it is desirable to provide over 5 the forked ends 39 of the arm 38, spring members 42, between which and the said forked ends, one fold of the material may be inserted and held while the other fold is manually held above the ring 41.

10 This completes the description of one embodiment of the present invention. It will be readily apparent that the apparatus described, consisting of the attachments shown and described in association with a sewing machine of the character 15 described, provide many advantages. Such apparatus enables the operator to perform the attachment of all accessories to an umbrella cover or case on the same sewing machine, and makes it possible to accomplish that with relatively small 20 and simple alteration, by the relatively easy substitution of a single, simple and readily accessible part of the machine. The attachments substituted are of simple construction and economical to make and use. They are easy to assemble and 25 dismantle and require no particular or new skill to operate.

What I claim as my invention is:

1. Mechanism for holding umbrella cover tips during machine stitching by a laterally vibratory 30 needle including a pivotally mounted lever, an L-shaped bracket secured to said lever and laterally spaced from the said needle to provide for manipulation of cover material by the operator, means for attaching one arm of said bracket to 35 said lever with the other arm thereof extending toward the path of said vibratory needle, an offset arm connected to said second arm to engage the bed plate of the machine adjacent said needle path, and a tip receiving element attached to said 40 offset arm and extending toward said needle path to fixedly support a tip in one end of said path.

2. Mechanism for holding umbrella cover tips during machine stitching by a laterally vibratory 45 needle including a pivotally mounted lever, an L-shaped bracket secured to said lever and laterally spaced from the said needle to provide for manipulation of cover material by the operator, means for attaching one arm of said bracket to 50 said lever with the other arm thereof extending toward the path of said vibratory needle, an offset arm adjustably connected to said second arm to engage the bed plate of the machine adjacent said needle path, and a tip receiving element adjustably attached to said offset arm and extending 55 toward said needle path to fixedly support a tip in one end of said path.

3. Mechanism for holding umbrella cover tips during sewing by a vibratory needle article attaching machine, comprising an arm having detachable connection with a pivoted lever forming 60 part of the article holding means of said machine, said arm extending toward the plane of vibration of the needle and sufficiently spaced 65 from said needle in a direction parallel with said plane to provide for manipulation of cover material by the operator, an arm extending at right angles to said first arm and having one end thereof removably and adjustably connected thereto 70 lengthwise of the latter arm and the other end thereof engaged with the work plate of said machine adjacent said needle, and a tip receiving element removably attached to said other end 75 of the arm and extending toward the plane of needle vibration and substantially parallel with

the first arm for supporting an apertured tip adjacent one end of the vibratory needle path.

4. Mechanism for holding umbrella cover tips during sewing by a vibratory needle article attaching machine, comprising an arm having connection with a pivoted lever forming part of the article holding means of said machine, said arm extending toward the plane of vibration of the needle and sufficiently spaced from said needle in a direction parallel with said plane to provide for manipulation of cover material by the operator, an arm extending at right angles to said first arm and having one end thereof connected thereto and the other end thereof engaged with the work plate of said machine adjacent said needle, and a tip receiving element attached to said other end of the arm and extending toward the plane of needle vibration for supporting an apertured tip adjacent one end of the vibratory needle path.

5. Mechanism for holding umbrella cover tips during machine stitching by a laterally vibratory needle comprising a pivotally mounted lever, an L-shaped bracket having one arm thereof secured to said lever and the other arm thereof extending toward the plane of needle vibration and laterally spaced from the stitching point to provide for manipulation of the cover material, an arm extending laterally of said other arm and having one end thereof adjustably secured thereto by a screw and slot connection, the other end of said last arm provided with an apertured head, and a tubular tip holding member having one end thereof adjustably secured in said aperture and with the other end thereof disposed adjacent the stitching point.
